DESIGN FOR A COMBINED COLLAR AND HANDLE FOR A COFFEE MAKER BOWL
OR THE LIKEHerbert G. Blakeslee, Evanston, Ill., assignor to Cory Corporation, Chicago, Ill., a corporation of Delaware

Application December 28, 1946, Serial No. 135,812

Term of patent 14 years

(Cl. D44—16)

To all whom it may concern:

Be it known that I, Herbert G. Blakeslee, a citizen of the United States, residing at Evanston, in the county of Cook and State of Illinois, have invented a new, original, and ornamental Design for a Combined Collar and Handle for a Coffee Maker Bowl or the like, of which the following is a specification, reference being had to the accompanying drawing, forming a part thereof, wherein:

Fig. 1 is a side elevational view of the combined collar and handle for a coffee maker bowl or the like, showing my new design;

Fig. 2 is a similar view, looking from the reverse side; and

Fig. 3 is a top plan view thereof.

The present application is a continuation-in-part of my application Ser. No. D-122,903, filed October 17, 1945, now abandoned.

I claim:

The ornamental design for a combined collar and handle for a coffee maker bowl or the like, as shown.

HERBERT G. BLAKESLEE.
